M. J. GEBHARDT

SPARK PLUG SHORT CIRCUITING DEVICE

Filed Oct. 7, 1926

Inventor

M. J. Gebhardt.

By Watson E. Coleman
Attorney

UNITED STATES PATENT OFFICE.

MICHAEL J. GEBHARDT, OF HOWARD LAKE, MINNESOTA.

SPARK-PLUG SHORT-CIRCUITING DEVICE.

Application filed October 7, 1926. Serial No. 140,200.

This invention relates to spark plug short circuiting devices and more particularly to a device operable from the driver's seat of the vehicle to short circuit a selected plug or 5 plugs during the operation of the vehicle to determine whether these plugs are missing.

A further object of the invention is to provide a device of this character which may be very readily applied to the vehicle, which 10 may be cheaply and durably constructed and which will be a general improvement in the art.

These and other objects I attain by the construction shown in the accompanying 15 drawing, wherein for the purpose of illustration is shown a preferred embodiment of my invention and wherein:—

Figure 1 is a side elevation showing spark plug short-circuiting apparatus constructed 20 in accordance with my invention;

Figure 2 is a fragmentary plan view thereof;

Figure 3 is a section on the line 3—3 of 25 Figure 2;

Figure 4 is a section on the line 4—4 of Figure 2.

Referring now more particularly to the drawing, the numeral 10 generally designates the head of a multi-cylinder internal combustion engine and 11 bolts by means of 30 which the head is held in position upon the cylinder block 12. Mounted in the cylinder head are the usual spark plugs 13. In accordance with my invention, I provide a bar

35 14 adapted to extend longitudinally of the engine head adjacent the spark plugs 13 and having at its ends legs 15, the lower ends of which are provided with out-turned feet 16 abutting the engine head and having openings 40 therein for the passage of the securing elements 11, so that the bar may be secured to the engine head. Pivoted upon the bar 14 adjacent each spark plug is a lever 17, one end of which is swingable into contact with

45 the upper or head end 18 of the central electrode of the spark plug. Adjacent each lever 17 and toward the rear end of the engine from the associated lever a support 19 is secured to the bar 14 having a split upper

50 end, as indicated at 20, the sections of which are compressible by a screw 21 to clampingly engage the housing 22 of Bowden wire 23 which is connected to the lever.

The numeral 24 indicates a support arranged adjacent the driver's seat of the ve-

hicle. This support preferably comprises the instrument board of the vehicle and has directed therethrough tubes 25, each having a flanged head 26 abutting the front face of the support. The rear ends of the tubes 25 are exteriorly threaded for the reception of a clamping nut 27 which combines with the flanged head 26 to clamp the support and maintain the tube rigidly in position and a coupling 28 by means of which the opposite end of the housing 22 is connected to the tube. Slidable in the tube 25 is a plunger 29, the inner end of which is secured to the Bowden wire 23 and the outer end of which has a head 30 whereby it may be shifted.

In the use of the device, if, in the operation of the vehicle, the engine is apparently missing on one cylinder, by consecutively drawing out the plungers 29, so that the associated levers 17 will move into engagement 75 with the adjacent spark plugs 18, these spark plugs will be consecutively shorted, the current passing from the head end 18 of the electrode through the lever 17, bar 14 and legs 15 to the head of the engine. When the plug of the missing cylinder is short-circuited, no difference will be noted in the operation of the engine and the operator may thus determine which cylinder is actually causing the trouble without leaving his 80 seat.

A device of this construction may be left continually applied to the head of the engine and will not in any way interfere with the insertion or removal of the spark plug or 85 with other operations which it is necessary to perform from time to time.

Since the construction hereinbefore set forth is capable of a certain range of change and modification without materially departing from the spirit of the invention, I do not limit myself to such specific structure except as hereinafter claimed.

I claim:—

A spark plug short circuiting device 100 adapted to be used in conjunction with a series of spaced plugs comprising a substantially U-shaped bar having feet adapted to bear against the head of an engine and disposed transversely to the lengths of the spark plugs, the intermediate portion of the said bar being disposed at an acute angle to the lengths of the spark plugs, levers pivotally mounted upon the intermediate portion of the bar and having end portions converg- 105 110

ing inwardly toward each other and disposed at acute angles with relation to the plane of the intermediate portion of the bar, each of said levers having one end portion 5 adapted to encounter one of the spark plugs when disposed transversely thereof, wires connected with the other ends of the levers

and combined clamp guides mounted upon the intermediate portion of the bar and receiving said wires.

10

In testimony whereof I hereunto affix my signature.

MICHAEL J. GEBHARDT.
